UNITED STATES PATENT OFFICE.

ROBERT J. BAKER, OF BALTIMORE, MARYLAND.

SOLDERING-IRON.

SPECIFICATION forming part of Letters Patent No. 243,097, dated June 21, 1881.

Application filed March 30, 1881. (No model.)

To all whom it may concern:

Be it known that I, ROBERT J. BAKER, a citizen of the United States, residing at Baltimore city, in the State of Maryland, have invented certain new and useful Improvements in Soldering-Irons; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

My improvement relates more particularly to what is known as the "hatchet" soldering-iron, consisting of a solid piece of copper beveled or wedge-shaped to form an edge, and which is forged from a solid bar of copper and requires frequent reforging to renew the working-edge. By my improvement the working-edge is formed from a plate of proper thickness secured so as to be fed to present a working-edge, so that no reforging is required, the plate being easily removed when used up. In such construction I preserve the required weight of the tool by the clamping parts or holder, so that there is, in fact, no repair or reforging necessary in using the tool, as the edge of the plate will maintain its proper form until worn down to a mere strip. In the adjustment of the plate out upon its seat as it wears a new one may be secured behind it in the holder, and serve, by means of a beveled lap-joining, to prevent the clamping action from buckling the plate when much reduced in size by wear. By this means I use a renewable plate as a soldering-edge, as contradistinguished from a solid body forged to a working-edge, renewable only by reforging.

Referring to the accompanying drawings, Figure 1 represents the solid hatchet soldering-iron now in general use. Fig. 2 represents my improved iron in perspective; Fig. 3, a similar view of the clamping plate-holder; Fig. 4, a cross-section on the line xx of Fig. 2; Fig. 5, a section on the line yy of Fig. 2, showing a plate about half worn or used up and a new plate secured in place and joining the worn plate with a lap-joint to prevent it from buckling under the clamping action of the holder; and Fig. 6, the soldering-plate proper.

In Fig. 1 I have shown the style of tool to which my improvement specially relates, and which is forged from a solid piece of copper of the required weight to produce the working-edge. A plate, a , of the proper size and shape, is cut from a sheet of copper, and constitutes the soldering-iron proper of the tool, its working-edge being formed of the thickness of the plate. These plates are sheared in quantities from sheets or plates of copper of the required thickness, and they are supplied to the trade for use with the clamping-holder. They may, however, be cut from waste pieces or from rolled strips.

The holder is in two parts, b and c , to form an adjustable clamp for the soldering-plate. In the construction shown these clamping parts are formed with seats d for the soldering-plate, and are made wedge-shaped at the ends next the working-edge of said plate. They are of sufficient size to give the required weight to the iron. These clamping parts are placed crosswise upon the shank or handle e , one part, b , being permanently fixed to the end thereof, and the other, c , is adapted for adjustment upon the shank. The seat-plate-receiving faces d of these clamping parts are formed with side clamping-guides, f , beveled or grooved on their inner sides, and the side edges of the soldering-plate are cut with corresponding bevels, so that when the plate is seated and the adjustable holder part is clamped upon said plate it will be held upon its seat by these bevels, as in a groove. The plate, when so seated and secured, projects beyond the wedge-shaped ends of the holder and presents the working-edge of the tool. The metal shank or handle has a screw-thread, and a nut, g , thereon serves as the means for setting the adjustable clamping part up so as to clamp the holder parts upon the soldering-plate. A pin, h , on one of the holder parts enters a hole in the other, and serves to preserve the relation of these parts with the plate and prevents the changing or turning of the adjustable part upon the shank. It is important that the gripe or clamping action of the holder upon the plate should be limited, and thereby prevent the plate being sprung or buckled between the securing-guides, and for this purpose a screw, i , is screwed into the fixed holder part, so as to

form an adjustable stop to limit the adjustment of the movable holder part toward the said fixed holder part. This construction of clamping holder parts allows them to be adjusted for different-sized plates, and also gives the advantage of an intermediate space between these parts for the circulation and radiation of heat in heating and using the tool.

An important matter in the invention is that the plates are produced each with a beveled end, in order that as the plate is fed out from the holder, and thereby becomes worn away or reduced in length, a new plate is inserted between the guides, so that the beveled ends of both will join or abut, the new plate overlapping, and thereby the new one is in effect thus made a continuation of the reduced one, and the latter is re-enforced and held upon its seat, so that it is prevented from buckling or springing when reduced. The plates may, however, abut squarely.

The soldering-plates may be made slightly tapering on their side edges in the direction of the working end, and the clamping-guides of corresponding conformation, which I find to give greater security to the retention of the plates in the holder, and especially when much reduced in length by use. The plate is unclamped when the working-edge is worn away, and it is fed out the required distance to give or renew the working-edge.

In a soldering-iron in which the working-edge is formed by a plate adjustably secured upon a clamping-guide, it is important that such clamping-guide be made adjustable to suit plates of different widths, that it be held by a clamping action of such guide exerted in the plane of the plate, and that such clamping force be tempered or set to prevent the buckling of the plate, which for straight seaming must have a perfectly true and straight working-edge.

Referring to the copper plate as being adapted to have its working-edge renewed as it is worn away, I have stated that such plate is fed from its holder, and I mean that it is adjusted out from the holder as it wears from use.

I claim—

1. In a soldering tool or iron, a holder for the soldering-plate proper, consisting of a fixed jaw or part, *b*, and an adjustable jaw or part, *c*, carried upon a screw-handle stem, *e*, each jaw having a guide-holding part, *f*, the adjustable jaw or part being adapted to effect the clamping action upon the working-plate in the plane thereof by being set in relation to the fixed clamping part substantially as described, for the purpose specified.

2. In a soldering iron or tool having a clamping-holder having a fixed and a movable part for a plate of a thickness to form the soldering-edge, the combination, with the movable part and its adjusting and clamping nut, of a set-stop carried by the fixed part, whereby to limit the clamping action of the holder upon the plate.

3. A soldering iron or tool consisting of a clamping-holder having a fixed and an adjustable part, a screw shank or handle upon which they are secured at right angles, a clamping-nut for the movable part, a plate forming the soldering-edge, a set-stop to limit the clamping action upon the plate, and a pin for maintaining the relation of the movable holder part to the plate and to the fixed holder part, substantially as described.

In testimony whereof I have affixed my signature in presence of two witnesses.

ROBERT J. BAKER.
